(57) **CLAIM**

The ornamental design for a wireless router, as shown and described.

DESCRIPTION

FIG. 1 is a front view of a wireless router;

FIG. 2 is a top view thereof;

FIG. 3 is a bottom view thereof;

FIG. 4 is a right-side view thereof; and,

FIG. 5 is a back view thereof.

Broken lines shown in FIGS. 1-5 illustrate portions of the wireless router that form no part of the claimed design.
